UNITED STATES PATENT OFFICE.

ELIJAH P. HARRIS, OF CHICAGO, ILLINOIS, ASSIGNOR TO THE PAYSON MANUFACTURING COMPANY, A CORPORATION OF ILLINOIS.

MEANS FOR OPERATING CASEMENT WINDOWS.

Application filed December 21, 1925. Serial No. 76,573.

My invention relates to improvements in means for operating casement windows; that is, windows hinged at one side and opened and shut by a swinging movement about an axis 5 which is usually vertical, although not necessarily so.

To maintain such a window in any position of adjustment when open, and to hold it shut, it has been the practice, in some cases, to provide an actuating member secured to the window sill near one side of the window, said member being mounted at one end to swing about a vertical axis substantially parallel to the axis of the window hinges, and its other 15 end having sliding engagement with a rod secured to and spaced from the bottom rail of the casement, whereby the window would be swung open and shut by actuating said member, said actuation being effected by 20 means of a handle and a worm and gear sector. Such movement is not reversible; that is, the window is held in any position, whether open or shut, and cannot be moved except by operating the worm and gear by means of the 25 handle. When the window sill on which the adjuster is installed is not horizontal, or where after installation said window-sill becomes warped, or where the window-frame itself becomes warped, the vertical axis of the 30 swinging rod does not remain parallel to the axes of the window hinges, and, as a result, the rod binds when the window is partially open, and such binding may prevent opening the window fully.

The object of this invention is to provide means for compensating for irregularities in the movement of the actuating rod with respect to the window, or vice versa, whereby said window may be opened and closed without 40 binding.

In the accompanying drawings, I have shown several embodiments of my invention.

Figure 1 is an elevation of part of a casement window.

Fig. 2 is a plan view thereof, partly in section,

Fig. 3 is a section on line 3—3, Fig. 1.

Fig. 4 is an enlarged central section of one of the parts.

Fig. 5 is a modification thereof.

Fig. 6 is a perspective view of a further modification.

Fig. 7 is an elevation, partly in section, of the compensating means in extreme position.

The window comprises the usual window-

frame 1 having the usual sill 2 in any suitable form, with the window-sash 3 hinged to the window-frame at one side thereof, one of the hinges being shown at 4. A housing or casting 5 is mounted on the window-sill, located preferably at the side near the hinge 4, and being secured in place by screws 6, or other suitable fastening means. The housing provides a bearing for a shaft 7 having a worm 8 thereon which meshes with a gear sector 9, the latter being mounted to turn about a vertical shaft 10. A rod 11 is secured at one end to said gear sector and when the window is closed is arranged as shown in Fig. 2, nearly parallel to the lower sash of the window. Said rod may be of any suitable cross-sectional outline, but is preferably round and passes through a circular opening 12 in a link 13, said link being pivoted at 14 to a bracket 15 comprising a pair of angles secured to said sash.

The free end of said link may thus swing up and down in a vertical plane about the horizontal pivot 14. The opening 12, as shown in Fig. 4, is provided preferably with a beveled edge 16 so that the contact between the wall of said opening and said rod is confined almost to an edge, thus permitting a deviation of the rod 11 from a position at right angles to the plane of the opening without causing binding.

Any suitable form of handle 17 may be provided for rotating the shaft 7 and thus cause the rod 11 to swing in a substantially horizontal plane about its vertical shaft, and thus swing the casement window about the vertical axes afforded by the hinges. The engagement of the gear sector with the worm results in holding the window in any position in which it may be left; that is partially opened, fully opened, or completely closed.

If the window-sill 2 is horizontal at the time of installation and the window-frame and sash are accurately made, the vertical axis about which the rod 11 swings will be exactly parallel with the vertical axis about which the window swings. However, if the window-sill is not horizontal, as is frequently the case, or if it subsequently warps, or the window-frame warps, the window hinges may be thrown out of alignment, or the housing 5 may be tilted from a horizontal plane, whereby when the window is swung open, ninety degrees for example, the rod 11 instead of being horizontal will slope down-

wardly or upwardly, or the window itself may deviate from its initial swinging movement. To prevent the binding between the rod 11 and the co-operating parts secured to the window-sash, the previously described two-part construction 13 and 15 is employed, whereby the link 13 may swing upwardly or downwardly to whatever extent is necessary within reasonable limits, to accommodate the irregularity in the movement of the actuating device, or of the sash itself.

In Fig. 7, I have shown how the link 13 swings downwardly, even to a position below the normal level of the window-sill, in extreme cases.

In Fig. 5, I have shown a modification of the link 13 in which the opening is provided with a bushing 18 having a rounded inner surface to prevent binding of the rod in different angular positions therein.

In Fig. 6, a further modification is shown wherein a supporting bracket 19 has a rivet 20 therethrough constituting a vertical bearing about which a depending U-shaped member 21 may turn. The downwardly extending arms engage opposite sides of the actuating rod and permit a certain up and down movement thereof without disengagement of the parts, the U-shaped member turning back or forth to whatever extent is necessary as the window swings to different positions of adjustment. While this modification has been used satisfactorily, it has limitations in that the downwardly extending arms cannot be too long or they will strike the window-sill when the window is closed and under extreme conditions of warping may not be long enough to insure engagement with the actuating rod when the window is opened. The lower part of the sash on some windows is quite narrow, thereby limiting the available space in which the bracket 19 may be secured. That is, in some cases, it cannot be secured high enough to permit the arms 21 to be made long enough to meet extreme conditions. For this reason, the forms shown in Figs. 4 and 5 are the preferred ones, wherein the link 13 may be made long enough and swing up and down far enough to remain operative under extreme conditions of warping, said link also being restored to its normal position when the window is shut, whereby it clears the window-sill, even though it is not mounted very high above the same.

In normal position, the bracket 15 is slight-

ly higher than the rod 11, as shown in Figs. 1 and 3, to facilitate installation thereof without too much interference by the rod 11 with the screw-driver or other tool which may be used. The gear sector 9 may be provided with a pin or stop 22 which engages the worm when said sector has rotated the desired amount, thus preventing opening the window beyond a ninety degree angle, or to whatever angle may be desired.

Although the invention has been described in connection with means for swinging a window about a vertical axis, it is obvious that it is not limited to windows of this general type, but may be employed in connection with other types of windows or ventilators turning about any axis, whether vertical, horizontal or inclined.

What I claim is:

1. In a device of the class described, a bracket having means for securing it to a window, a link secured to said bracket by means of a horizontal pivot, whereby said link may swing in a vertical plane, said link having an opening therethrough with a beveled edge, a rod passing through said opening and conforming in cross-sectional outline thereto, a pivotal support at one end of said rod, and means for causing said rod to swing about its pivot and open and shut said window, said link compensating for irregularities in the movement of said rod with reference to said window and without binding.

2. A device of the class described comprising a bracket adapted to be secured to a hinged window, a housing secured to a stationary support inwardly of said window, a rod pivotally secured to said housing on an axis normally parallel to the axis of the window hinge, manually operable means carried by the housing for swinging said rod upon its pivot and means for transmitting motion from the rod to the bracket for operating said window without binding, said means comprising a member pivoted to said bracket and having a passage through which the rod extends for accommodating movement of the pivotal axis of said rod out of parallelism with the window hinge and varying angularities of the rod with respect to the window during the opening and closing of the latter.

In testimony whereof, I have subscribed my name.

ELIJAH P. HARRIS.
